ATTORNEY.

UNITED STATES PATENT OFFICE.

ELMER A. SPERRY, OF CHICAGO, ILLINOIS, ASSIGNOR TO FRANK S. TERRY,
OF SAME PLACE.

ELECTRIC BATTERY.

SPECIFICATION forming part of Letters Patent No. 397,945, dated February 19, 1889.

Application filed March 24, 1888. Serial No. 268,447. (No model.)

To all whom it may concern:

Be it known that I, ELMER A. SPERRY, a citizen of the United States, residing at Chicago, in the county of Cook and State of Illinois, have invented a new and useful Electric Battery, of which the following is a specification.

My invention relates to electric batteries or cells, and has for its object to provide certain novel features of construction, more particularly illustrated in the accompanying drawings, wherein—

Figure 1 is a cross horizontal section taken through the jar below the top and looking upward against the top. Fig. 2 is a plan view of the metallic carbon-supporting ring. Fig. 3 is a vertical section taken through the jar. Fig. 4 is a detail of the device for securing the carbon-ring.

Like parts are indicated by the same letter in all the drawings.

A is a jar.

B is the cover thereto, having the ledge B'.

B² is a dependent rim adapted to pass inside the top of the jar.

B³ is a central cylindrical zinc-guide in the center of the top, being flared at its lower end at B⁴, as indicated.

C C are carbons secured each in a metallic ring, D D. These rings are secured each to the central ring, D', and are formed each with two lips, D² D², through which passes the screw D³, whereby the lips may be drawn together, and thus the metallic rings be contracted to clamp the end of the carbon. Two or more of these rings are formed with caps D⁴, having each a raised cylinder, D⁵, thereon, which said cylinders are bored out to receive screws D⁶, which thus secure the metallic rings composing the carbon-holders tightly to the lower side of the cover.

D⁷ is a similar ring-cap having the cylinder D⁸, from which projects the screw-rod D⁹, upon which is placed the thumb-screw D¹⁰.

E is a zinc piece corrugated on its lower end, having the thumb-screw E' at its upper end and the aperture E² passing through it. At its lower end is the washer E³.

F is a body of paraffine, which entirely fills the inner portion of the lid or cover and cov-

ers the metallic rings and the clamped portion of the carbons when the whole is in position, as indicated in Fig. 3.

G is a washer about the zinc and resting on the cover.

J is a collar about the zinc resting upon such washer, and K is a pin through the zinc, and thus the zinc is kept from passing too far into the jar.

The use and operation of my invention are as follows: The upper end of each carbon is placed in a metallic ring, D. This ring may be made of any desired material—preferably, of course, of lead—and is independent in all portions, except where it is secured to or made continuous with the central metallic ring, D'. The ring D is broken at one side and has the lips, which are drawn together by the screw D³. By turning this screw the carbon may be clamped in position and a very strong pressure applied to its upper end, so as to diminish the resistance thereof. The top of the jar is made of wood or porcelain or other suitable material, and is made so as to cover the jar and its rim to pass therein, as shown in Fig. 3.

As many carbons as may be required can be arranged in this manner about the central ring. The metallic rings filled with the carbons are then placed in position on the inner side of the jar-cover, the central ring, D', encircling the cylindrical pendant B³. The depth of the rings D and D' is a trifle less than the depth of the brim or rim B². The carbon-carrying rings are now secured in position by means of any desired number of screws D⁶, which are introduced through suitable apertures in the top or cover and pass into the apertures in the cylindrical projections D⁵ on the caps D⁴. When these screws are driven home, the carbons are securely attached, together with their clamping metallic rings, to the inner portion of the cover. The cover is now placed with the carbons upward, and is filled with paraffine or other similar insulating material to the top of the rim, so as to cover all of the metallic portions of the rings which support the carbons, and also to fill the cover of the jar with the insulating material, from which nothing but the central pendant of the cover and the carbons project.

The lips on the rings are placed in such a position as to be included within the circle whose center is the center of the ring D' and whose circumference is tangential to the 5 points on the rings D D farthest from the center of the rings D'. The zinc is passed through the aperture in the pendant B³, and is held in position by the collar, washer, and pin. The zinc is corrugated at its lower end 10 to furnish the largest possible surface for chemical action. The washer E³ keeps the zinc from contact with the carbons, and should be of insulating material. The pendant B³ is hollowed or flared out internally toward its 15 lower extremity, as indicated at the point B⁴, so that the zinc E touches the top or the cover of the jar in a single plane, and that plane practically identical with the top of the cover. The connections are made to the jar in the 20 usual manner, the carbon wire being placed under and secured by the thumb-nut D¹⁰ and the zinc wire being placed in the aperture E² and clamped by the set-screw E'. The arrangement of the carbons in this manner enables 25 me to clamp their upper ends very securely and very tightly and about their entire circumference. The arrangement of carbons about the central ring, D', also permits of their being brought very closely together 30 at their upper ends, and also permits the carbon wire to be attached at the nearest possible point to the zinc, or to the center of all the carbons, thus giving the shortest possible route of the current between such point 35 of delivery and the carbons. The paraffine makes a complete insulation for the carbons, and the pendant B³, shaped as shown internally, prevents the liquid in the jar from assuming such a position on any part of the 40 cover as to connect directly from carbons to zinc, and thus short-circuit the battery. In any commotion or violent agitation of the jar the liquid which it contains will or may be thrown against the under portion of the cover; 45 but it will immediately drop off of the edges of the pendant B³, and will not form in a coating at any place so as to short-circuit.

By having the cylindrical projections D⁵ upon the caps D, which projections pass upward through suitable apertures in the top or cover, we are enabled to have a long aperture into which to introduce the securing-screw, and thus we are enabled to tightly secure the 50 carbon-holding rings to the top. The battery 55 as arranged according to my invention has nothing projecting above the cover except the parts to which the wires are actually secured and the screws which attach the carbon-holding rings to the cover, thus making a jar with 60 a very beautiful exterior.

Having thus described my invention, what I claim, and desire to secure by Letters Patent, is as follows:

1. In a battery, the combination of a jar 65 with a cover, a series of carbons, and carbon-securing rings, said carbons and rings being secured to and entirely beneath the cover.

2. In a battery, the combination of a jar with a cover, a series of carbons, carbon-securing rings attached to the lower side of the 70 cover, and a body of insulating material on the under side of said cover, in which the carbon-securing rings are entirely submerged.

3. In a battery, the combination of a jar with a cover provided with a pendent rim, a 75 series of carbons, carbon-clamping rings secured to said cover within the rim, and a body of insulating material filling the space inclosed by the rim and submerging the clamping-rings.

4. In a battery, the combination of a jar with a cover provided with a pendent rim and a somewhat longer pendent zinc-guide, a 80 series of carbons, and carbon-supporting rings secured to the cover in the space between the rim and the guide.

5. In a battery, the combination of a jar with a cover provided with a pendent rim and a somewhat longer pendent zinc-guide, a 85 series of carbons and carbon-supporting rings secured to the cover in the space between the rim and the guide, and a body of insulating material in the space between the rim and the guide and submerging the clamping-rings.

6. In a battery, the combination of a jar, a cover provided with a pendent rim inside the jar, and a zinc-guide internally enlarged at its lower end, with a series of carbons and clamping-rings secured to said cover, a zinc 100 passed through the guide, and a body of insulating material between the cover and guide and submerging the carbon-clamping rings.

7. In a battery, a carbon-clamping device consisting of a series of contractible rings.

8. In a battery, a carbon-securing device consisting of a series of contractible rings provided each with a clamping device.

9. In a carbon-securing device, a series of contractible rings provided each with a clamping device and all secured to a central supporting-piece.

10. In a battery, a carbon-securing device consisting of a central ring with a series of contractible rings secured thereto, in combination with a jar-cover, on the lower side of which such carbon-securing rings are secured.

11. In a carbon battery, the combination of a jar with a cover provided with a pendent 110 rim and a somewhat longer central pendent zinc-guide, the inner surface of which is enlarged toward its lower end, carbon-securing rings attached to the cover between the rim and guide, insulating material in which rings 115 are submerged, and a zinc of such size as to engage the cover near the top of the guide only, so as to prevent the liquid in the jar from making a short circuit on the lower side of the cover between the zinc and carbons.

12. In a carbon battery, the combination of a carbon-securing device with a cover, said cover provided with apertures and said car-

bon-securing device with projecting chambered pieces which pass through said apertures, so as to provide a long bearing for the securing-screws on top of the cover.

5 13. In a carbon battery, a zinc, round at its upper end, provided with straight longitudinal corrugations extended along its lower por-

tion to afford increased contact-surface with the liquid.

ELMER A. SPERRY.
